UNITED STATES PATENT OFFICE.

MIDDLETON CRAWFORD, OF BROOKLYN, NEW YORK.

BOILER-FEED REGULATOR.

SPECIFICATION forming part of Letters Patent No. 334,691, dated January 19, 1886.

Application filed May 8, 1885. Serial No. 164,746. (No model.)

To all whom it may concern:

Be it known that I, MIDDLETON CRAWFORD, a citizen of the Dominion of Canada, and residing in the city of Brooklyn, in the county of

5 Kings and State of New York, have invented certain new and useful Improvements in Steam - Boiler Feed - Regulators; and I do declare the following to be a full, clear, and exact description of the invention, such as will 10 enable others skilled in the art to which it appertains to make and use the same, reference being had to the accompanying drawings, and to the letters and figures of reference marked thereon, which form a part of this 15 specification.

This invention relates to devices for automatically feeding water to steam-boilers; and the novelty consists in the construction, arrangement, and adaptation of parts, as will 20 be more fully hereinafter set forth, and specifically pointed out in the claims.

The essential object of the invention is to utilize the ordinary conditions of a steam-generator to operate a feed valve or pump, 25 so that when the water in the generator reaches a certain low level the steam of the generator will automatically set into operation a train of devices to inject more water into the boiler, and that when the water has 30 attained a proper level in the boiler the said water will operate said devices to cut off further supply.

Various thermostatic appliances have been devised for analogous purposes, and in steam-traps it is old to operate a valve upon thermostatic principles.

The present invention seeks to simplify the principle as applied to steam-boilers. It embodies a device which is simple in operation, 40 not liable to get out of order, and which is efficient in service.

The invention is illustrated in the accompanying drawings, which form a part of this specification, and in which—

45 Figure 1 is a central section; Fig. 2, a detail perspective of the valve; and Fig. 3, a diagram, on a smaller scale, showing the relation of the novel parts to a boiler.

For purposes of this description it is not 50 necessary to show any particular means for supplying feed - water to the boiler, and it

will be understood that any proper and approved contrivance for this purpose may be employed.

Referring to the drawings, A designates an 55 ordinary steam-boiler. It has a steam-pipe, A², and a water-pipe, A', as shown, the purposes of which will presently appear, the former being arranged above and the latter below a desired water-level.

F designates a supporting - frame, which 60 may be suspended from a wall or otherwise supported so that it will at all times maintain a proper relation to the generator A and its high-water level a.

B and C designate steam - chambers, which 65 may be made of a single casting, and they are connected by a hollow neck, b, at the upper portion of which is formed a valve-seat, b'. The upper part of the chamber B has a suitable stuffing-box and receives the end of the steam-pipe A², while the chamber C has a stuffing-box at its lower portion which receives the water-pipe A'.

D designates a valve having a central cavity 75 corresponding to the interior of the tube A', and it operates in connection with the seat b'. It is carried on the upper end of the pipe A', and its stem, which comprises a considerable portion of the pipe A' within the chamber C, is of brass or other metal which has 7c marked expansive and contractile qualities, sensitive to changes in high temperatures.

A properly - packed cylinder, C', connects 80 with the chamber C, and a piston-head, e, carried on a rod having a rack, e², is arranged within the cylinder, so as to be forced outward therein by steam-pressure in the chamber C, a spring, c', serving to hold the piston against such pressure with a constant force. 90 The rack - bar e² projects beyond the cylinder and engages a pinion, C², which by any suitable connections is adapted to operate a steam pump or valve, or other water-feeding device. (Not shown.) The valve - stem has 95 longitudinal external grooves, d, which extend for about the length of the neck b, and they serve as steamways when the valve is off its seat.

The devices thus far described are uncomplicated, inexpensive, and may be applied to 100 boilers now in use. They operate automatic-

ally to keep the water in the boiler at a uniform level and allow but a limited fluctuation from a predetermined water-level.

The operation will be obvious. The frame 5 F and its supported devices B C having been arranged so that the valve D will be approximately on a level with a proper water-line, (see *a*, Fig. 3,) the steam-pressure in the chamber B and the contraction of the valve-stem, 10 by reason of its being held in the water of the boiler, holds the valve D tightly to its seat. In this condition there is high pressure in the chamber B and low pressure in the chamber C, and the spring *c* is exercising its force to 15 close and hold closed the feed-water devices. (Not shown.) As the water lowers in the boiler, it correspondingly falls in the pipe A' and in the valve portion thereof, allowing the steam from the chamber B to enter the 20 interior of the valve-stem and by its heat to expand the same to raise the valve D from its seat *b*'. This action admits steam around the valve head and through the recesses *d*, which steam, entering the chamber B, forces back the 25 piston C', and, consequently, through the rack-bar *c*', revolves the pinion C', to project more water into the boiler by operating the feed-valve or other device. (Not shown.) The water entering the boiler raises the level in 30 the valve-stem, which, contracting by reason thereof, forces the valve D back to its seat. The pressure reduces in the chamber C. The spring *c*' forces the piston inward toward the chamber C, and at the same time the pinion 35 C', by its proper connections, shuts off the water supply. By this arrangement but very little fluctuation is allowed in the water-level, and the cooling of the boiler by large injections is avoided.

40 I attach importance to the arrangement of the two chambers B C in their described relation to each other and to the thermostatic valve and feed-water-controlling piston.

It will be noticed that the inclined position 45 of the thermostatic contrivance in its relation to the boiler serves a function in allowing a limited deviation of the water in the boiler to affect a multiplied surface in the valve-tube A'. This, in increasing the sensitiveness of 50 the valve, is important in this invention, as a small rise of water in the boiler will affect a large lineal surface in the pipe.

Water of condensation may be trapped out 55 of chamber C by any known and well-approved means.

I am aware that in trapping out water of condensation a thermostatic tube has been before used.

What is claimed as new is—

1. The combination, with a steam-boiler and feed-water connections, of a valve having a tubular thermostatic stem arranged upon the plane of the desired water-level, as and for the purposes set forth. 60

2. The combination, with a boiler and feed-water connections, of a valve arranged with a tubular thermostatic stem upon the approximate plane of the desired water-level, and steam and water connections whereby the expansion of said stem by reason of contact of steam will open the valve to operate the feed devices, and the contraction of said stem by reason of contact of water will close the valve and allow the feed to be cut off, as set forth. 65 70

3. In combination with a steam-boiler and feed-water connections of two connected steam-chambers, a thermostatic valve arranged in the upper chamber and extending through the lower chamber, and a piston connected with the lower chamber, arranged to operate 75 the feed-water connections to inject water into the boiler when the said valve is off its seat in the upper chamber, as set forth. 80

4. In a steam-boiler regulator, substantially as described, the combination, with the boiler, 85 chambers, as B C, and pipe-connections, of a valve having a tubular thermostatic stem, *b*, arranged upon an incline with the boiler, as and for the purposes specified.

5. In a steam-boiler appliance, as described, 90 the chambers B C and neck *b*, having valve-seat *b*', a steam-pipe connecting the upper chamber with the steam above the water-level, and a water-pipe extending from the interior of the boiler below the water-level through 95 the chamber C, and carrying a valve having a hollow stem of expansive metal, all combined and operating substantially as and for the purposes set forth. 95

6. In an automatic boiler-regulator, substantially as described, the valve-seat *b*', arranged on a line with the desired water-level in the boiler, a hollow thermostatic valve, as D, a steam chamber to receive steam when the water lowers and the valve is lifted, and 105 a piston operated by such steam to open the feed-water devices, as set forth. 100

7. The casting B C *b* *b*', as described, combined with the boiler, the pipes A' A'', the valve D, the piston, and feed-water connections C', all arranged and operating as and for the purposes set forth. 110

In testimony whereof I affix my signature in presence of two witnesses,

MIDDLETON CRAWFORD.
